(No Model.)

G. T. WARWICK.
SADDLE FOR VELOCIPEDES.

No. 429,587.

Patented June 3, 1890.

UNITED STATES PATENT OFFICE.

GEORGE T. WARWICK, OF SPRINGFIELD, MASSACHUSETTS, ASSIGNOR TO THE
WARWICK CYCLE MANUFACTURING COMPANY, OF SAME PLACE.

SADDLE FOR VELOCIPEDES.

SPECIFICATION forming part of Letters Patent No. 429,587, dated June 3, 1890.

Application filed February 26, 1889. Serial No. 301,268. (No model.)

To all whom it may concern:

Be it known that I, GEORGE T. WARWICK, a subject of the Queen of Great Britain, residing at Springfield, in the county of Hampden and State of Massachusetts, have invented new and useful Improvements in Saddles for Velocipedes, of which the following is a specification.

This invention relates to improved saddles for velocipedes, being especially designed for use on Safety bicycles, although, as will appear from the description hereinafter given, they are applicable for use on velocipedes of other classes, the object of the invention being to increase the efficiency of the saddle-spring-supporting devices, and to render, through movable saddle-supports, the mounting and dismounting of the saddle of more easy and convenient accomplishment; and the invention consists in the construction and combination of parts, all substantially as will be hereinafter more fully described, and set forth in the claims.

In the drawings, Figure 1 is a side elevation and partial vertical section of the present improved saddle. Fig. 2 is a vertical cross-section of the supporting parts thereof on the line $x-x$, Fig. 1, looking in the direction of the arrow x' . Fig. 3 is a horizontal section on the line $y-y$, Fig. 1, and a plan view of the parts below such line. Fig. 4 is a view similar to Fig. 3, but with the parts in changed positions. Fig. 5 is a plan view of the under side of the saddle; and Fig. 6 is a sectional view in detail, to be hereinafter referred to.

In the drawings, B represents the saddle-post of a Safety bicycle or other kind of velocipede, and is preferably of tubular form at its upper portion, whereby the angular carrying-arm 36 of the saddle may be vertically adjusted by moving its vertical portion up or down, the same being supported in place in said tubular saddle-post by its adjustable collar 25, resting on the end of said saddle-post.

The saddle-supporting devices comprise a yoke or carrier-block 37, maintained on the horizontal portion of said supporting-arm 36 and adapted for a horizontal movement thereon, as will be hereinafter described. Pending from said yoke, as clearly shown in Figs. 1 and 2, are two tubular spring-cases 39, which

are rigidly secured by their upper ends to said yoke 37, the latter having vertical perforations therethrough in a line with the bore of said cases. Within said cases are placed suitable springs 40, either spiral or of rubber or other suitable material. (See Fig. 1.) Two plungers 41 are fitted to move vertically in said spring-cases 39, the lower ends of which bear against the upper ends of the springs 40, and the upper ends of said plungers are united by a saddle-plate 42, rigidly secured thereto, the upper side of said plate being curved, as shown in Fig. 1, and a clamp-plate 43 is secured against said saddle-plate by a bolt 44, passing through the latter and said clamp-plate, on the upper end of which is screwed a nut, as shown in Fig. 1. The said saddle-plate and clamp-plate are provided with corresponding grooves in their inner adjoining faces, 70 which grooves are indicated by o and serve to receive the portions of the saddle-frame which are attached to said plate. The said saddle-frame 45 is constructed, preferably, from a piece of heavy steel wire, and is made by first bending said wire to form a circular spring-base 46, and from thence extending said wire rearwardly (curving its two parts where it passes between the plate 42 and the clamp-plate 43) and beyond the latter, forming in 80 each of said two parts $c-c$ a coil-spring d , and from said springs d extending said wire parts slightly farther to the rearward and forming on the end of each a loop m of oblong form, to provide thereby a support for the central portion of the metallic saddle-seat frame 47, said frame 47 being 85 made, preferably, of sheet metal and having its central portion bent, as shown in Fig. 2, to partially inclose the said loops m , to 90 which said frame is rigidly secured by brazing or other suitable means, if desired, or it may be simply hooked onto said loops. From said saddle-seat frame 47 the said wires are brought toward the center and extend in two 95 lines $v-v$ toward the forward end of the saddle and terminate in a circular head 48, which serves to receive the upper end of a spring 49, of coiled wire or other suitable material, the base of said spring resting upon 100 the said base 46. It is preferred to place a metallic cup-shaped socket or seat 46' on said

base, which may be secured thereto in any suitable manner, as by brazing or riveting, such construction serving the better to maintain the spiral spring 49 against displacement. 5 The said lines *v v* of the wire constituting a portion of said saddle-frame have their ends welded or brazed together at or near said circular head 48, and they constitute a spring-arm 50, flexibly supporting that part of the 10 weight which is brought to bear upon the saddle at or near its front end, supplemented by the support thereto which is afforded by the spring 49, interposed between said arm 50 and the lower flexible arm of the frame 15 which the said portions *c c* constitute, the coil-springs *d d* providing an easy and flexible support for the rear end of the saddle. The saddle-seat 51 is made, preferably, from leather and has its rear end suitably riveted 20 to the said seat-frame 47 and its front end attached in any suitable manner to the end of said spring-arm 50. In order that lateral strain or deflection on the forward supporting-spring 49 may be withstood or avoided, a 25 plate 17 is secured in the circular head 48 of the saddle-frame spring, having a pendent ear-piece 18, to which is pivoted the upper end of a rod 19, which plays through a perforation in the bottom of the cup-shaped socket 30 46', as seen in Fig. 6. The pivot-line being transversely of the saddle, the said rod may have all requisite swinging motion longitudinally of the saddle, but no lateral motion.

From the above-described construction of 35 said saddle it will be seen that its spring-frame is made from a single piece of suitable spring-wire, and that it affords the greatest ease of motion under the weight of the rider, and when supplemented by the interposition 40 between its upper and lower forward portions of the spring 49 its resistance to deflection is more or less increased and its flexibility is not impaired. The attachment of the saddle-frame by the said curved portion of its 45 lower arm between the curved plates 42 and 43 admits of adjusting the saddle to varying longitudinal planes. The said yoke 37, intermediate of its vertical perforations for the plungers 41, is of hub form, the axis of which 50 is horizontal and at right angles to the common plane of the axes of said plunger-perforations, and said hub is axially bored for the support therein and passage therethrough of the horizontal extension 36^a of the angular 55 arm 36. On the upper side of the said yoke 37, intermediately pivoted in ear-pieces thereof, is a latching-lever *g*, having its rearward arm hooked on its under side, as at 56, and its forward arm upwardly extended, as at 57, 60 and said hooked end is depressed by gravity when there is no weight on the seat to force it (the seat) into a contact with the said forward arm 57 of the latch-lever, and forms an abutment for the rearward end of the extension of the arm 36, preventing the yoke from 65 sliding on said arm.

The vertical member 36^b of the angular arm

36 is provided with a rearwardly-extending horizontal bar *h*, secured in place by brazing its collar or otherwise rigidly attaching it to 70 said vertical member, and said horizontal bar passes loosely through and is supported in a pending hanger-piece 58 from said yoke 37. *i* represents a collar to slide on the said bar *h*, and is confined in any adjusted position by the set-screw 59. The said collar is rearwardly tapered, and on one side thereof has a hole 60.

On one of the tubular cases 39 is a tubular 80 casing 62 for a spring-plunger catch 63, extending horizontally and at right angles to and into proximity with the said bar, and also in a line with said hole 60 in the collar *i* thereon.

13 represents a hooked arm suitably supported from the arm 36, and to the same is connected the one end portions of a pair of spiral springs 64 64, which by their other ends are connected to laterally-projected pins 75 of the said yoke 37, and when the weight 90 of a rider is on the saddle to secure its depression and the disengagement thereby of the latch-lever *g* from the end of the horizontal arm member 36^a by said springs the saddle, and the rider as well, is drawn forward, 95 guided by and supported on said horizontal member until the spring-plunger catch 63 enters the hole in the adjustable collar *i*, when the saddle-yoke and other supporting parts movable therewith are rigidly held. 100

On the upper end of the saddle-supporting post B is a rigid horizontal radial arm 65, provided with a vertical perforation or socket 66 near its end, at each side of which the arm is extended in wings 67, the upper surfaces of 105 which are slightly downwardly and outwardly inclined, and on the vertical member of the arm 36 is fixed a radial arm 68, carrying a vertical casing 69 for a spring-plunger catch 70. The saddle-supporting arm 36 is loosely 110 fitted in the upper end portion of the tubular post B and vertically adjustable thereon, as hereinbefore described, and is capable of a rotary motion on said post when the spring-plunger catch 70 is out of engagement with 115 the hole 66 in the radial arm 65.

At the time of mounting the machine the saddle is to be in the rearmost position, (indicated in Figs. 1 and 3,) but is with its longitudinal median line at right angles to the line of the backbone. Then, when the weight 120 of the rider is on the saddle, the catch *g* is released, freeing the saddle-yoke and all the parts of the saddle movable on said horizontal bar members 36^a and *h* to the action of the 125 spring, and thereby said movable parts are drawn forward until the catch 63 enters the hole 60 in the adjustable collar *i*. The rider then swings around with the saddle, so that the length thereof ranges with the length of 130 the machine, and in such swinging movement the end of the catch 70 rides on the inclined wing 67 and drops into the hole 66. The saddle-supporting parts, which are movable on

the stationary parts of or fixed to the saddle-post, are, as will be plain, at the time of riding by the catch 63 locked against endwise movement and by the catch 70 locked against any 5 revolution on the saddle-post.

As a seat for velocipedes adapted for longitudinal and partial rotary motions, substantially as described, is intended largely for use in the form of machines known as "Safety" 10 bicycles, and such thereof as are adapted for use by ladies, and it being understood that the normal riding position in this class of machines is somewhat forward of the rear wheel and so close to the handle-bars that the mounting of the seat, when in its normal riding position, by a lady is quite difficult, it will be apparent that on affording to the saddle the capabilities for its movement, as described, when the seat is projected and confined in 15 its rearward position and the one farther away from the handle-bars, and with its longitudinal line at right angles to the length of the machine, the rider may most easily dispose herself in the saddle, after which the saddle 20 is readily caused to resume its normal position.

What I claim as my invention is—

1. The combination, with a horizontal arm member adapted to be supported on a suitable part of the velocipede-frame as the saddle-post thereof, of the saddle-yoke movable on the said horizontal arm, and a spring applied between said saddle-yoke and a stationary part of the machine-frame for drawing 35 said yoke forward on said arm, substantially as described.

2. The combination, with a horizontal arm member adapted to be supported on a suitable part of the velocipede-frame as the saddle-post thereof, of the saddle-yoke movable on the said horizontal arm, a spring applied between said saddle-yoke and a stationary part of the machine-frame for drawing the saddle forward on said arm, and a catch applied between said yoke and the end of said 45 arm to engage the latter and prevent the movement of the yoke thereon in the direction of its spring-pressure, substantially as described.

3. The combination, with a horizontal arm member adapted to be supported on a suitable part of the velocipede-frame as the saddle-post thereof, of the saddle-yoke movable on said horizontal arm, an adjustable stop to limit the movement of said yoke on said arm, and a spring applied between said saddle-yoke and a stationary part of the machine-frame for drawing said yoke forward, substantially as described.

4. The combination, with a horizontal arm member adapted to be supported on a suitable part of the velocipede-frame as the saddle-post thereof, of the saddle-yoke on said horizontal arm, a spring applied between said saddle-yoke and a stationary part of the machine-frame for drawing said yoke forward, a stop to limit the movement of said yoke on

said arm, and a spring-catch supported on the yoke adapted to engage said stop and prevent a movement of the yoke in a direction against its spring, substantially as described.

5. The combination, with the saddle-post and the angular arm comprising the horizontal and vertical members 36^a and 36^b, supported thereon, and the bar *h*, supported from said vertical member 36^b and ranging parallel with the member 36^a, of the saddle-yoke movable on said horizontal member 36^a and provided with a hanger-piece, through which 80 said bar *h* is adapted to play, substantially as described.

6. The combination, with the saddle-post and the angular arm comprising the horizontal and vertical members 36^a and 36^b, supported thereon, and the bar *h*, supported from said vertical member 36^b and ranging parallel with the member 36^a, of the saddle-yoke movable on said horizontal member 36^a and provided with a hanger-piece 58, through 85 which said bar *h* is adapted to play, and a spring for moving said yoke forward, substantially as described.

7. The combination, with the angular arm 36, comprising the horizontal and vertical members 36^a and 36^b, and the adjustable collar *i*, having the latching-socket 60, of the yoke movable on said horizontal member 36^a, provided with the spring-plunger catch, substantially as described.

8. In combination, a horizontal member or arm adapted to be supported on the frame of a velocipede, the yoke movable on said arm, the saddle vertically guided and spring supported on said yoke, and a latching-lever intermediately pivoted and having the upwardly-projecting angular arm normally adapted to confine the yoke against movement in one direction on the horizontal arm, and to be released from said confining engagement on the depression of said saddle to abut against its angular arm, substantially as described.

9. In combination, the frame of a velocipede and a saddle carried on a post-like part, one of said parts, as the frame, having a vertical socket, into which the other or post-like part of the saddle fits, and is supported against vertical movement and is freely rotatable, and a catch device on the one part, as the saddle-carrying post, and adapted to engage with the other for locking the carrying-post against rotary movement, and all whereby, when said catch device is released from its engagement, the saddle may be readily swung in its normal 120 plane of support from the longitudinal line of the machine to or about to a right angle therewith, for the purpose set forth.

10. The combination, with the saddle-post *B*, socketed at its upper end and provided 130 with the radial arm 65, having a latch-socket 66, of the angular arm 36, comprising the vertical and horizontal members 36^b and 36^a, the former rotatable in said post-socket and pro-

- vided with the spring-plunger latch, and a saddle mounted on said horizontal member, substantially as described.
11. The combination, with the saddle-post 5 B, socketed at its upper end and provided with the radial arms 65, having a latch-socket 66, and one or more lateral downwardly-inclined wings 67, of the angular arm 36, comprising the vertical and horizontal members 10 36^b and 36^a, the former rotatable on said post-socket and provided with the spring-plunger latch, and a saddle mounted on said horizontal member, substantially as described.
12. The combination, with the frame of a 15 velocipede, of an arm comprising the vertical and horizontal members, the former having a bearing for rotation in the frame, and a saddle-yoke supported and longitudinally movable on the horizontal member, a spring 20 for drawing said saddle forward, a latching device for confining said yoke in its rearmost position on the horizontal member, a latching device for confining said yoke when in its forward position, and a locking device for 25 confining said vertical member against rotation, substantially as described.
13. A velocipede-saddle having a metallic frame consisting of an upper and a lower arm, each formed of two lines of spring-wire, 30 substantially as described, united at their rear ends, the front end of said upper arm having a free deflecting motion when acting under a load, combined with a seat-frame engaging with the rear end of said frame, and a saddle-seat applied over said seat and saddle frames, substantially as set forth.
14. A velocipede-saddle having a metallic frame consisting of an upper and a lower arm, each formed of two lines of spring-wire, 40 substantially as described, united at their rear ends, a spring inserted between the front ends of said arms, combined with a seat-frame engaging with the rear end of said frame, and a saddle-seat applied over said seat and saddle frames, substantially as set forth.
15. A velocipede-saddle having a metallic frame consisting of an upper and a lower arm, each formed of two lines of spring-wire, 50 substantially as described, united at their rear ends, said lower arm having the spring-coils *d* and the front end of said upper arm having a free deflecting motion when acting under a load, combined with a seat-frame engaging with the rear end of said frame, and 55 a saddle-seat applied over said seat and saddle frames, substantially as set forth.
16. A velocipede-saddle having a metallic frame consisting of an upper and a lower arm, each formed of two lines of spring-wire, substantially as described, united at their 60 rear ends, said lower arm having the spring-coils *d* and a spring inserted between the front ends of said arms, combined with a seat-frame engaging with the rear end of said frame, and a saddle-seat applied over said 65 seat and saddle frames, substantially as set forth.
17. A velocipede-saddle having a metallic frame consisting of an upper and a lower arm, substantially as described, united at 70 their rear ends, the front end of said upper arm having a free deflecting motion when acting under a load, combined with a seat-frame engaging with the rear end of said frame, and a saddle-seat applied over said seat and saddle frames, substantially as set forth. 75
18. A velocipede-saddle having a metallic frame consisting of upper and lower arms, each formed of two lines of spring-wire, substantially as described, united at their rear 80 ends, a cup-shaped bearing-socket 46', secured on the forward end of the lower arm, a spring resting on and between said bearing-socket and the front end of said upper arm, combined with a seat-frame engaging with the 85 rear end of said spring-frame, and a saddle-seat applied over said seat and spring frames, substantially as described.
19. A velocipede-saddle having a metallic frame consisting of upper and lower arms, 90 each formed of two lines of spring-wire, substantially as described, united at their rear ends, a cup-shaped and perforated bearing-socket 46', secured on the forward end of the lower arm, a vertical rod pivotally attached 95 to the forward end of the upper frame and adapted to have a swinging motion longitudinally of the saddle, but rigidly supported against lateral movement and playing through the perforation of said socket-cup, and a 100 spring resting on and between said bearing-socket and the front end of said upper arm and surrounding said rod, combined with a seat-frame engaging with the rear end of said spring-frame, and a saddle-seat applied over 105 said seat and spring frames, substantially as described.
